UNITED STATES PATENT OFFICE.

HARRY E. DOANE, OF CINCINNATI, OHIO, ASSIGNOR TO THE J. D. RANDALL COMPANY,
OF CINCINNATI, OHIO, A CORPORATION OF OHIO.

COLLAR-STUFFING MACHINE.

1,084,075.

Specification of Letters Patent.

Patented Jan. 13, 1914.

Application filed January 3, 1911. Serial No. 600,396.

To all whom it may concern:

Be it known that I, HARRY E. DOANE, a citizen of the United States of America, and resident of Cincinnati, county of Hamilton, 5 and State of Ohio, have invented certain new and useful Improvements in Collar-Stuffing Machines, of which the following is a specification.

My invention relates to that class of collar-stuffing machines in which means are provided for rotating a mass of straw, so that a different part of the bottom of the mass is presented to each forward stroke of a feed rod, which reciprocates diametrically 15 across the bottom of the mass, pulls the straws therefrom, and feeds them into a collar.

The object of my invention is a means for rotating the straw which is at once positive and capable of being actuated at a 20 minimum expenditure of power. This object is attained by the means described in the specification, and illustrated in the accompanying drawings, in which,

25 Figure 1 is a perspective view of a collar-stuffing machine embodying my invention, the feed tube being shown broken off and the ends being brought together, to economize space. Fig. 2 is a top plan view of the machine 30 illustrated in Fig. 1, the legs of the machine being omitted for the sake of clearness of illustration. Fig. 3 is a sectional view along irregular line 3—3 of Fig. 2, looking in the direction of the arrows. Fig. 4 is a 35 detail perspective view upon an enlarged scale, of a part of the feed rod and feed tube. Fig. 5 is a sectional view of the base, the ring and the lower end of the hopper.

A circular base A is secured to the stand 40 B, and has a diametric way, a, in which is located a feed rod, D. In alinement with the way, a, a feed tube, d, is secured to the base, A. Tube, d, is made of a size to receive the feed rod, D, upon the forward 45 stroke of the rod. Feed rod, D, is connected by wrist pin, d', with the pitman, d², which is secured to disk, d³, which in turn is secured to the end of the main driving shaft, M. Base, A, has a circular offset, a', which 50 affords a circular seat in which is formed a circular groove, a⁴, into which projects a circular flange of a rotatable ring, E, which has external teeth, e, and internally projecting radial pins, e'. Base, A, is slotted 55 at a⁵, for the reception of a pinion, e², which

meshes with the teeth, e. Pinion e² is secured upon a vertical stud shaft, e³, which is journaled in the base, A, and carries at its lower end a beveled pinion, e⁴, which in turn meshes with a beveled pinion, e⁵, which is mounted upon a horizontal shaft, e⁶, which is rotated by means of chain and gear wheel, e⁷, e⁸, respectively. The chain, e⁷, passes over a gear wheel mounted upon the main driving shaft, M. Base, A, has likewise a circular offset, a², which affords a seat for a circular collar, g, which is secured to the lower end of hopper, G. Collar, g, rests loosely upon the seat, a², of the base and out of contact with the ring, E. 60 65 70

In operation, straw being placed in the hopper, G, and a weight, H, being placed thereon, if desired, the power being thrown on, the rotation of the main driving shaft, E', imparts simultaneous reciprocation to 75 the feed rod, D, and rotation to the ring, E. Pins, e', of the ring, E, engaging the straw, impart the rotation of the ring to the straw, so that a different part of the bottom of the mass of straw is presented to the feed rod, 80 upon each of its forward strokes. Should the friction between the straw and the hopper be greater than the friction between the hopper and its seat, a², the straw in rotating, will carry the hopper around with 85 it. If the friction between the straw engaged by the pins, e', and the straw in the hopper be less than the friction between either the straw and the hopper, or the friction between the hopper and its seat, 90 a², the pins, e', will rotate only the straw which is adjacent to the pins. Hence the machine will work with the minimum amount of friction between these parts. 95 Flange, E', working in groove, a⁴, prevents straw from accumulating between the ring, E, and its seat.

What I claim is:—

1. In a machine of the type specified, the combination with a hopper, of a rotating member below said hopper, pins extending inwardly from said rotating member and engaging the circumference of the body of straw inclosed by said rotating member to carry the same around, a reciprocating feed rod below said rotating member adapted to engage the straw thus being carried around by said pins, and means for rotating said member, substantially as specified. 100 105

2. In a collar-stuffing machine, the com- 110

bination of a base having a circular way formed therein, a ring mounted rotatably upon the way and having inwardly projecting radial pins, a hopper resting upon the base above the ring and out of contact therewith, a feed rod located in the base below the ring, and means for simultane-

ously rotating the ring and reciprocating the feed rod.

HARRY E. DOANE.
